UNITED STATES PATENT OFFICE.

GEORGE WINTER JONES, OF WINNIPEG, MANITOBA, CANADA, ASSIGNOR TO MACNAB AND ROBERTS, LIMITED, OF WINNIPEG, CANADA.

OVEN.

1,127,259.

Specification of Letters Patent.

Patented Feb. 2, 1915.

Application filed February 3, 1913. Serial No. 745,906.

To all whom it may concern:

Be it known that I, GEORGE WINTER JONES, of the city of Winnipeg, in the Province of Manitoba, Canada, have invented 5 certain new and useful Improvements in Ovens, of which the following is the specification.

My invention relates to a hot air oven for baking bread, cakes, etc., and the object of 10 the invention is to provide an inexpensive, durable and efficient oven of large capacity heated by hot air, the parts being arranged and constructed as hereinafter more particularly described, and later pointed out in the 15 appended claim.

Figure 1 is a side elevation of the oven. Fig. 2 is an end view of the same. Fig. 3 is a longitudinal vertical sectional view through the oven, the section being taken in the plane 20 denoted by the line X—X' Fig. 2. Fig. 4 is a longitudinal horizontal sectional view through the oven, the section being taken in the plane denoted by the line Y—Y' Fig. 2. Fig. 5 is a horizontal sectional view through 25 the oven, the section being taken in the plane denoted by the line Z—Z' Fig. 2. Fig. 6 is a horizontal sectional view through the oven, the section being taken in the plane denoted by the line T—T' Fig. 2. Fig. 7 is 30 a horizontal sectional view through the oven, the section being taken in the plane denoted by the line L—L' Fig. 2. Fig. 8 is a vertical cross sectional view through the oven, the section being taken in the plane denoted by the line H—H' Fig. 1.

In the drawing like characters of reference indicate corresponding parts in each figure.

1 represents a fire brick wall supporting 40 one side of the fire grate 2 which is carried at the opposite side by a fire brick bridge 3, providing between them and beneath the grate an ash pit 4.

5 is a brick pier located at some distance 45 from the bridge, the bridge and pier supporting a number of I beams 6, which carry metallic plates forming a floor 7.

8 is an inner casing substantially rectangular in cross section, formed from suitable 50 sheet metal plates 9 connected one to the other by angle irons 10, which casing has the forward portion resting upon and securely fastened to the floor 7, and the rear portion thereof passing to the ground line indicated

at 11 and inclosing the wall 1 and the bridge 65 3, it being noticed that the bridge and wall are connected by a further fire brick wall 12.

13 is an outer casing substantially rectangular in cross section and of the same form as the casing 8, which outer casing is 60 also formed from sheet metal plates 14 connected also one to the other by angle irons 15 and having the forward portion thereof resting on the floor 7 and the rear end thereof of passing to the ground line and supplied 65 with a door 16 which opens directly through the inner casing to the fire pit 17 immediately above the grate bars.

18 and 19 are two similar diverging flues resting on the floor 7 and passing from the 70 fire pit to the forward end of the oven where they communicate with upwardly directed flues later referred to.

21 is a central flue resting on the floor and passing from the fire pit forwardly to the 75 inner casing where it terminates in a dead end.

22 are cross plates located above the flues and carried by suitable longitudinally disposed angle irons 23 and 24 secured to the 80 side of the inner casing 8. The plates carry plates 25 forming the bottom of a baking oven 26 inclosed at the top by further cross plates 27 carried by angle irons 28 having the ends thereof supported by longitudinally 85 disposed angle irons 29 also secured to the sides of the inner casing.

30, 31 and 32 are I beams located on the plates 27 and passing the full length of the inner casing and secured permanently in 90 position by angle iron supports 33 passing across the ends of said casing.

34 are further plates carried by the I beams 30, 31 and 32 and also by angle irons 35 secured to the sides of the inner casing. 95 These plates support a tile floor forming the bottom of an oven 36 inclosed at the top by plate 37 carried by angle irons 38 supported at their ends by longitudinally disposed angle irons 39 secured to the inner face of 100 the inner casing.

I beams 40, 41 and 42 bear on the plates 37 and are secured to the ends by suitable angle iron cross bars 43, fastened to the inner face of the inner casing.

105 It is here to be noticed (see Fig. 5) that the I beams 40 and 42 terminate at the rear end a short distance from the rear end of

the inner casing, while the forward end of the I beam 41 terminates a short distance from the forward end of the inner casing.

5 44 are plates carried by the I beams 40, 41 and 42 and by angle iron bars 45 secured to the sides of the inner casing.

10 The flues 18 and 19 communicate rearwardly with the fire box and forwardly with upwardly directed flues 46 and 47 located between the casings, which latter flues open to further horizontally disposed flues A and B formed by the plates 27 and 34, the I beams 30 and 32 and the walls of the inner casing.

15 48 and 49 are further upright flues located between the casings at the rear end of the oven, which flues connect directly at the top with the flues A and B.

20 E and F are two further horizontally disposed flues located between the plates 37 and 44, and between the I beams 40, 41 and 42, which flues connect directly through the openings reserved at G and H between the rear ends of the I beams 40 and 42 and the 25 rear end of the inner casing with the flues 48 and 49.

Dead air spaces are formed between the I beams 40, 42 and the walls of the inner casing.

30 The flues E and F connect directly with the chimney L located at the front of the oven, which chimney is provided with a damper 50.

35 Suitable cleaning gates 51 are located at the ends of the various flues to allow them to be readily cleaned out when desired.

40 The hot air and gases pass from the first pot forwardly through the flues 18 and 19, upwardly through the flues 46 and 47, backwardly through the flues A and B, upwardly through the flues 48 and 49, and thence across and forwardly through the flues E and F directly to the chimney where they

are freed. Accordingly the ovens 26 and 36 are heated evenly and efficiently.

45 In order to prevent undue radiation and consequent loss of useful heat units I have filled in the space between the two casings with mineral wool 52 or other such material which will effectually prevent any loss of 50 this kind. The top plates 44 are also covered with mineral wool.

The material to be baked is placed in the ovens on the tiled floors by opening the doors 53 and 54 located at the front of the 55 outside casing.

What I claim as my invention is:—

In an oven, outer and inner casings, ovens located one above the other within the inner casing, horizontally directed flues located between the ovens, diverging flues beneath the bottom oven, a fire box communicating with the rear ends of the flues beneath the bottom oven, a central horizontal flue between said diverging flues terminating in a 65 dead end, vertically directed flues being in communication rearwardly and forwardly with the rear and forward ends of the flues between the ovens, the vertically directed flues communicating with the rear ends of 70 the flues between the ovens being also in communication with the rear end of the flues beneath the bottom oven, all of said vertically directed flues being between the casings, a chimney communicating with the 75 forward ends of the flues above the top oven, a damper in the chimney, and a non-conducting material interposed between the casings.

Signed at Winnipeg this 4 day of December, 1912.

GEORGE WINTER JONES.

In the presence of—

W. H. HUNTER,
G. A. WHEPLEY.
